UNITED STATES PATENT OFFICE

PERRY FLORA, OF OWINGSVILLE, KENTUCKY.

INCUBATOR-ALARM.

948,504.

Specification of Letters Patent.

Patented Feb. 8, 1910.

Application filed April 16, 1909. Serial No. 490,279.

To all whom it may concern:

Be it known that I, PERRY FLORA, citizen of the United States, residing at Owingsville, in the county of Bath and State of Kentucky, have invented certain new and useful Improvements in Incubator-Alarms, of which the following is a specification.

This invention relates to thermostatic alarms and has for its object to provide a strong, durable and thoroughly efficient device of this character especially designed for attachment to an incubator for sounding an alarm in case the temperature of the incubator rises above or falls below the predetermined degree.

A further object of the invention is to provide a signal or alarm including a standard having spaced contacts slidably mounted thereon and co-acting with a contact member carried by the damper actuating bar, said movable contacts being adjustable vertically of the standard and adapted to close the circuit through the signal bell and sound the alarm.

A still further object of this invention is generally to improve this class of devices so as to increase their utility, durability and efficiency, as well as to reduce the cost of manufacture.

Further objects and advantages will appear in the following description, it being understood that various changes in form, proportions, and minor details of construction may be resorted to within the scope of the appended claims.

For a full understanding of the invention and the merits thereof and also to acquire a knowledge of the details of construction and the means for effecting the result, reference is to be had to the following description and accompanying drawings, in which:

Figure 1 is a perspective view of a signal or alarm constructed in accordance with my invention showing the same in position on an incubator; Fig. 2 is an enlarged side elevation partly in section of the standard showing the position of the movable contact with respect thereto; Fig. 3 is a transverse sectional view taken on the line 3—3 of Fig. 2.

Corresponding and like parts are referred to in the following description and indicated in all the views of the drawings by the same reference characters.

The thermostatic alarm forming the subject matter of the present invention, is prin-

pally designed for attachment to an incubator and by way of illustration is shown in connection with an incubator of the ordinary construction in which 5 designates the body portion, 6 the lamp casing, and 7 the regulator bar having one end thereof connected with the damper 8 and its opposite end connected with a thermostat of any approved construction.

The device comprises a standard 9 having a suitable base 10 for attachment to the top of the incubator and provided with a longitudinally disposed slot 11 and spaced flanges 12 defining a guiding groove for the reception of a sliding block 13. Extending laterally from the block 13 are spaced arms 14 and 15 to one of which is secured a relatively stationary contact 16, while the other arm is provided with a movable contact 17 preferably in the form of a screw as shown. A lock nut 18 engages the threads of the screw 17 and is adapted to bear against the arm 15 for locking the relatively movable contact 17 in adjusted position. Extending through the slot 11 is a clamping screw 19 which engages a correspondingly threaded opening in the block 13 so that the block may be adjusted vertically of the standard and securely locked in adjusted position.

Connected with a binding screw 20 on the base or support 10 of the standard is one terminal of an electrical circuit including a battery 21, the other terminal of the circuit being connected with the bracket 22 of the damper actuating bar 7. Connected in the circuit is a bell or other suitable signal 23 and a switch 24 by means of which the circuit may be interrupted to cut out the alarm when desired. Secured to the bar 7 at a point adjacent the free end thereof is a contact member 25 preferably in the form of a flat strip of metal to the fixed end of which is pivotally secured a clip 26 which latter is provided with a socket for the reception of the bar 7 and is locked in engagement with said bar by means of a clamping screw 27. The free end of the contact member or bar 25 terminates in an enlarged head 28 adapted to close the current through the contact members 16 and 17 when the temperature of the incubator rises above or falls below a predetermined degree thereby to notify the operator or attendant of such change in temperature and thus prevent injury to the eggs within the incubator.

When the temperature of the incubator is normal the enlarged head 28 of the contact member 25 is disposed intermediate of the contacts 16 and 17. Should the temperature fall below a predetermined degree, however, the head 28 will engage the lower contact 16 and close the circuit through the conductor 29, battery 21 and bar 7 and sound the signal bell 23. Should the temperature of the incubator rise above normal the circuit will be closed through the upper contact member 17, battery 21 and bar 7 and sound the alarm in the manner before stated.

Attention is here called to the fact that the members 14 and 15 carrying the contacts may be adjusted vertically of the standard so as to cause the sounding of the alarm or signal when the temperature reaches any predetermined degree while by manipulating the screw 17 the movable contact may be adjusted to a nicety thereby to render the device extremely sensitive in operation. While the signal or alarm is shown in connection with an incubator, it will of course be understood that it may be used with equally good results wherever a device of this character is desired for sounding an alarm upon the rise or fall of the temperature.

Having thus described the invention, what is claimed as new is:

1. The combination with a movable damper actuating bar, of a standard having spaced guide flanges connected at their upper ends by a transverse strip constituting a stop, a block slidably mounted between said flanges, and provided with laterally extending arms, a relatively stationary contact carried by one of the arms, a screw threaded in the other arm and constituting a movable contact, a lock nut engaging the threads of the screw for locking the movable contact in adjusted position, and a contact carried by and disposed at substantially right angles to the damper actuating bar and adapted to engage the contacts on the movable block for closing the circuit, thereby to sound an alarm.

2. The combination with a movable damper actuating bar, of a standard having guide flanges spaced apart at their lower ends and connected at their upper ends by a transverse strip to form a stop, a block slidably mounted between said flanges and provided with integral laterally extending arms,

a relatively stationary contact secured to one of the arms, a screw threaded in the other arm and constituting a movable contact, a clamping nut engaging the threads of the screw for locking the movable contact in adjusted position, means for locking both arms in different positions of adjustment with relation to the height of the standard, and a flat strip of metal detachably secured to and disposed at right angles to the damper actuating bar and adapted to engage the contacts on the block for closing the circuit thereby to sound the alarm.

3. The combination with an incubator, of a damper actuating bar, a standard having a base secured to the incubator and provided with a binding screw, spaced contacts adjustable on the standard, an electrical circuit having one terminal thereof secured to the binding screw of the standard and its opposite end connected with the actuating bar, said electrical circuit including a signal and switch, a contact member detachably secured to the actuating bar and provided with a head operating between and adapted to engage the contacts on the standard for closing the circuit and a clip pivotally mounted on one end of the contact member and having a socket formed therein for the reception of the damper actuating bar.

4. The combination with an incubator, including a damper actuating bar, of a standard secured to the incubator and provided with spaced vertically adjustable contacts, an electrical circuit connected with the standard and actuating bar respectively and including a signal, a contact member comprising a flat strip of metal detachably secured to and disposed at a right angle to the actuating bar and provided with an enlarged head adapted to engage the contacts on the standard for closing the circuit, a clip pivotally mounted on one end of the flat strip of metal and having its intermediate portion provided with a socket for the reception of the damper actuating bar, and a fastening device extending through the flat metal strip and the adjacent end of the clip for locking the clip in engagement with the actuating bar.

In testimony whereof I affix my signature in presence of two witnesses.

PERRY FLORA. [L. S.]
